(57) **CLAIM**

The ornamental design(s) for a heated hair straightener, as shown and described.

DESCRIPTION

FIG. 1 is a perspective view of the heated hair straightener in accordance with the principles of the present disclosure FIG. 2 is a top plan view of the heated hair straightener; FIG. 3 is a bottom plan view of the heated hair straightener; FIG. 4 is a left side elevation view of the heated hair straightener;

FIG. 5 is a right side elevation view of the heated hair straightener;

FIG. 6 is a front axial view of the heated hair straightener; and,

FIG. 7 is a rear axial view of the heated hair straightener. The broken lines shown indicate unclaimed portions of the article and form no part of the claimed design.

1 Claim, 4 Drawing Sheets
